UNITED STATES PATENT OFFICE.

GEORGE L. GRIFFIN, ROBERT ALONZO GRIFFIN, CHELSEA BEACH GRIFFIN, AND HERBERT ELVIA GRIFFIN, OF HOUSTON, TEXAS.

MECHANISM FOR CONVERTING MOTION.

SPECIFICATION forming part of Letters Patent No. 740,423, dated October 6, 1903.

Application filed November 10, 1902. Serial No. 130,774. (No model.)

To all whom it may concern:

Be it known that we, GEORGE L. GRIFFIN, ROBERT ALONZO GRIFFIN, CHELSEA BEACH GRIFFIN, and HERBERT ELVIA GRIFFIN, citizens of the United States, residing at Houston, in the county of Harris and State of Texas, have invented a new and useful Mechanism for Converting Motion, of which the following is a specification.

10 The present invention relates to mechanism for converting reciprocatory into rotary motion; and the objects are to provide a practical apparatus of this character in which rotary motion may be imparted to a driven member without occasioning any dead-centers and to provide simple means for reversing the direction of motion of the driven member whenever it is found desirable or necessary. The preferred means for accomplishing these objects is illustrated in the accompanying drawings; but it will be apparent that the construction shown is open to changes and modifications.

In the drawings, Figure 1 is a view in elevation of the mechanism. Fig. 2 is a vertical longitudinal sectional view through the same on an enlarged scale. Fig. 3 is a vertical transverse section, and Fig. 4 is a detail perspective view of one of the pawls.

30 Similar numerals of reference indicate corresponding parts in all the figures of the drawings.

In the embodiment of the invention illustrated suitable supports are employed, preferably in the form of spaced standards 10, connected at their upper and lower ends by cross-pieces 11, the lower cross-pieces being attached to a base 12 and the upper pieces 11 being connected by a brace 13. The cross-pieces 11 are furthermore provided on their inner opposing faces with bearing-blocks 14, in which is slidably mounted the reciprocatory member. This member is preferably in the form of an open frame comprising upper and lower sets of longitudinal bars 15, connected by upright end bars 16, one of the end bars being connected, by means of a rod, as 17, with the piston of an engine or with any other driving means. The driven member 50 is constructed as follows: Parallel shafts 18 and 19 are journaled in the standards 10, the

shaft 19 constituting the driven shaft. These shafts each carry a sprocket-wheel 20, around which runs an endless cable, preferably in the form of a chain 21, that has a stretch located contiguous to each set of the longitudinal bars 15. This chain is formed of flat-faced link-plates secured together by journal-rivets, the ends of the outer link-plates being spaced apart and constituting oppositely-disposed shoulders 22. Pivoted to and between each set of bars is a pawl 23, having oppositely-extending dogs 24, the free ends of which are bifurcated, as shown at 25, so as to embrace the intermediate links of the chain, 65 the terminals of said dogs being concave, as shown at 26, so as to fit the ends of the outer links, as clearly shown in Fig. 2. The dogs of each pair are so arranged with relation to each other that when one is in engagement with the chain the other will be housed between the side bars. A controlling-lever 27 is pivoted intermediate its ends to the outer end bar 16, said lever being normally held against movement by a dog 28, 75 pivoted thereto and engaging a rack 29, secured to the adjacent end of the reciprocatory member. Tension-bars 30 are attached to the controlling-lever on opposite sides of the pivot and extend between the longitudinal 80 bars of each set, their inner ends being provided with offset spaced lugs 31. A stem 32, pivoted to and between a pair of spaced ears 33, secured to each pawl, is slidably mounted in the offset lugs 31 of the adjacent tension-bar, said stem having a buffer-block 34, which is located between the lugs 31. Tension-springs 35 are arranged on opposite sides of this block, bearing against the same and against the lugs 31. The springs are so arranged that when the lever is thrown in one direction one of the springs carried by each stem will be compressed, while the other will be correspondingly released, so that one of the dogs of each pawl will be yieldingly 90 thrown into engagement with the adjacent stretch of chain.

By referring to Fig. 2 it will be seen that the dogs engage in opposite directions upon the upper and lower stretches of the cable, and thus when the reciprocatory member is moved in one direction one of the dogs will

engage the adjacent stretch of the cable and move the same, while the other will ride freely over said cable, because of its yielding tension. On the return movement the reverse will take place, and thus the cable will be continuously moved in one direction and will impart a similar movement to the driven shaft. Whenever it is found desirable or necessary to reverse the rotation of said shaft, it is only necessary to throw the controlling lever to an opposite position. This will compress the opposite springs and release the tension of those now in action, thereby simultaneously reversing the pawls and bringing the opposite dogs into coacting relation with the cable. It will be apparent that there is no dead-center to this mechanism and that the power imparted to the driven shaft remains constant throughout the full stroke of the piston. At the same time the structure is extremely simple, as is also the means for reversing the direction of motion of the driven shaft.

From the foregoing it is thought that the construction, operation, and many advantages of the herein-described invention will be apparent to those skilled in the art without further description, and it will be understood that various changes in the size, shape, proportion, and minor details of construction may be resorted to without departing from the spirit or sacrificing any of the advantages of the invention. The term "cable" as used in the specification and claims is intended to describe any flexible endless connection and can be either in the form of a chain, a wire-rope, or a belt passing around pulleys.

Having thus described our invention, what we claim as new, and desire to secure by Letters Patent, is—

1. In mechanism of the class described, the combination with a reciprocatory driving member, of a driven member, including a stretch of cable located longitudinally of the direction of movement of the reciprocatory member, and separate cable-engaging devices carried by the reciprocatory member, either of said devices being movable into direct engagement with the same stretch of cable to move the same in opposite directions.

2. In mechanism of the class described, the combination with a reciprocatory driving member, of a driven member, including a stretch of cable located longitudinally of the direction of movement of the reciprocatory member, and oppositely-extending dogs carried by the reciprocatory member, either of said dogs being movable into direct engagement with the same stretch of cable to move said stretch in opposite directions and thereby reverse the direction of movement of the driven member.

3. In mechanism of the class described, the combination with a reciprocatory driving member, of a driven member including a stretch of cable located longitudinally of the reciprocatory member, and a pawl pivoted to

the reciprocatory member and carrying oppositely-projecting dogs alternately movable into engagement with the same stretch of cable.

4. In mechanism of the class described, the combination with a reciprocatory driving member, of a driven member including a stretch of chain having an oppositely-arranged series of shoulders, and a pawl pivoted to the reciprocatory member and carrying oppositely-projecting dogs respectively and alternately movable into engagement with the series of shoulders.

5. In mechanism of the class described, the combination with a reciprocatory driving member, of a driven member including a cable having shoulders on its opposite side faces, and a dog pivoted to the reciprocatory member and having its free end bifurcated, said end embracing the cable and detachably engaging with the shoulders thereof.

6. In mechanism of the class described, the combination with a reciprocatory driving member, of a driven member including a chain-cable having oppositely-disposed shoulders on its opposite side faces, and a pawl pivoted intermediate its ends to the reciprocatory member and having oppositely-projecting dogs, the free ends of the dogs being bifurcated and arranged to embrace the cable, said ends being alternately movable into engagement with the shoulders of said cable.

7. In mechanism of the class described, the combination with a reciprocatory driving member, of a driven member including a stretch of cable, oppositely-projecting dogs carried by the driving member and alternately movable into and out of direct engagement with the same stretch of cable to move the latter in opposite directions, and means for moving said dogs into and out of engagement with said stretch.

8. In mechanism of the class described, the combination with a reciprocatory driving member, of a driven member including a stretch of cable, oppositely-projecting dogs carried by the driving member and alternately movable into and out of direct engagement with the same stretch of cable to move the latter in opposite directions, and common means for simultaneously moving said dogs respectively into and out of engagement with said stretch.

9. In mechanism of the class described, the combination with a reciprocatory driving member, of a driven member including a stretch of cable, a pawl pivoted to the driving member and carrying oppositely-projecting dogs that are alternately movable into and out of engagement with the cable to move the latter in opposite directions, and means engaging the pawl for swinging the same.

10. In mechanism of the class described, the combination with a reciprocatory driving member, of a driven member including a cable, a pawl pivoted to the driven member and carrying oppositely-projecting dogs that

are alternately movable into and out of engagement with the cable, springs acting in opposite directions upon the pawl, and means for varying the tension of the springs to swing

5 the pawl upon its pivot.

11. In mechanism of the class described, the combination with a reciprocatory driving member, of a driven member including a cable, a pawl pivoted to the driven member 10 and carrying oppositely-projecting dogs that are alternately movable into and out of engagement with the cable, springs acting in opposite directions upon the pawl, and a tension-bar slidably mounted upon the driving 15 member and having portions bearing against both springs.

12. In mechanism of the class described, the combination with a reciprocatory driving member, of a driven member including a 20 stretch of cable, a pawl pivoted to the driving member and carrying oppositely-projecting dogs that are alternately movable into and out of engagement with the cable to move the latter in opposite directions, a stem connected to the pawl and having a buffer-block, 25 springs arranged on the stem on opposite sides of and bearing against the buffer-block, and a tension-bar slidably mounted upon the driving member and having opposite portions 30 bearing against both springs.

13. In mechanism of the class described, the combination with a reciprocatory driving member, of a driven member including a stretch of cable, a pawl pivoted to the driving member and carrying oppositely-projecting dogs that are alternately movable into and out of engagement with the cable to move the latter in opposite directions, a stem connected to the pawl and having a buffer-block, 35 springs arranged on the stem on opposite sides of and bearing against the buffer-block, a tension-bar slidably mounted upon the driving member and having opposite portions bearing against both springs, and a lever pivoted upon the reciprocatory member and connected to the tension-bar.

14. In mechanism of the class described, the combination with a reciprocatory driving frame, comprising spaced side bars, of a driven 50 member including an endless cable having oppositely-moving stretches respectively located contiguous to the said bars, oppositely-arranged dogs carried by each bar and alternately movable into engagement with the contiguous stretch of the cable, and means for simultaneously moving all the dogs.

15. In mechanism of the class described, the combination with a reciprocatory driving frame, comprising spaced side bars, of a driven 55 member including an endless cable having oppositely-moving stretches respectively located contiguous to the said bars, and a pawl

pivoted upon each bar and having oppositely-disposed dogs alternately movable into and out of engagement with the cable upon the 65 swinging movement of the pawl.

16. In mechanism of the class described, the combination with a reciprocatory driving frame, comprising spaced side bars, of a driven member including an endless cable having 70 oppositely-moving stretches respectively located contiguous to the said bars, a pawl pivoted upon each bar and having oppositely-disposed dogs alternately movable into and out of engagement with the cable upon the 75 swinging movement of the pawl, and means for simultaneously swinging the pawls in opposite directions.

17. In mechanism of the class described, the combination with a reciprocatory driving frame, comprising spaced side bars, of a driven member including an endless cable having 80 oppositely-moving stretches respectively located contiguous to the said bars, a pawl pivoted upon each bar and having oppositely-disposed dogs alternately movable into and out of engagement with the cable upon the 85 swinging movement of the pawl, and means having a yielding connection with each pawl for swinging the same.

18. In mechanism of the class described, the combination with a reciprocatory driving frame, comprising spaced side bars, of a driven member including an endless cable having 90 oppositely-moving stretches respectively located contiguous to the said bars, a pawl pivoted upon each bar and having oppositely-disposed dogs alternately movable into and out of engagement with the cable upon the 95 swinging movement of the pawl, and a controlling-lever 100 pivoted intermediate its ends upon the frame and having a yielding connection with each pawl.

19. In mechanism of the class described, the combination with a reciprocatory driving member, of a revoluble member including a stretch of cable arranged contiguous to the reciprocatory member, and oppositely-arranged connections carried by one member and alternately movable into engagement 105 with the other member, whereby said stretch of cable may be moved and the revoluble member rotated in opposite directions.

In testimony that we claim the foregoing as our own we have hereto affixed our signatures 110 in the presence of two witnesses.
